UNITED STATES PATENT OFFICE.

JOHN LA ROCK, OF CHICAGO, ILLINOIS, ASSIGNOR OF ONE-HALF TO TERENCE F. MCKENNA, OF CHICAGO, ILLINOIS.

PIPE-WRENCH.

1,161,777.

Specification of Letters Patent. Patented Nov. 23, 1915.

Application filed January 9, 1915. Serial No. 1,292.

To all whom it may concern:

Be it known that I, JOHN LA ROCK, a citizen of the United States, and a resident of Chicago, in the county of Cook and State 5 of Illinois, have invented certain new and useful Improvements in Pipe-Wrenches; and I do hereby declare that the following is a full, clear, and exact description thereof, reference being had to the accompanying drawings, and to the characters of reference marked thereon, which form a part of this specification.

This invention relates to improvements in wrenches designed more particularly for 15 grasping cylindric articles, such as pipes and the like, to turn them or to hold them from turning, as desired, but is also adapted to hold polygonal objects such as nuts, the heads of bolts and the like.

20 Among the objects of the invention is to provide an improved wrench of this character which is so constructed and arranged as to permit it being worked in close quarters as, for instance, to enable it to be applied to and turn a pipe that is located 25 against a wall, or to adapt it to be used for operating on the nested pipes of a coil or like structure.

30 A further object of the invention is to provide an improved wrench of this character which, while finding its greatest efficiency when applied to a pipe of a given size, yet is capable of efficient use with pipes of larger or smaller sizes and the parts are 35 so arranged as to permit the wrench to be readily adjusted to such larger or smaller pipes.

40 A further object of the invention is to provide in a wrench of this character a construction wherein the jaws of the wrench may be made to grasp the pipe or other article to be held and turned with great power and, at the same time, to provide a construction which is very compact so as to 45 permit its use in close quarters without clashing with adjacent objects.

Other objects of the invention are to improve and simplify wrenches of the character referred to, and the invention consists 50 in the matters hereinafter set forth and more particularly pointed out in the appended claim.

55 In the drawings:—Figure 1 is a plan view of a wrench embodying my invention showing the same applied to a pipe located flat

against a wall. Fig. 2 is a side view of a wrench. Figs. 3 and 4 are partial plan views showing the capacity for adjustment of the wrench.

As shown in the drawings, 10 and 11 designate the jaws of the wrench. One of the jaws is made integral with a hand lever 12. The other is made integral with a short lever 13 which is pivoted, as by means of a pivot pin or rivet 14, to the hand lever 12 adjacent to the jaw 10. The said lever 13 is provided at its rear end with a rearwardly opening curved notch 15 which is engaged by a curved ended extension 16 of a second hand lever 17 that is pivoted, as by means of a pivot pin 18 to the hand lever 12. The hand lever 17 is arranged in the plane of the jaw lever 13 and lies over the hand lever 12 so as to be capable of swinging across the said hand lever 12 in both directions, as indicated in Figs. 3 and 4.

The jaws are curved on their inner faces to conform to the circle of a pipe of a size to which they are most efficiently adapted, and are formed on their inner curved faces 80 with teeth or serrations 19. The curved faces of the said jaws comprise together slightly more than one-half of the circle of the pipe to which they are adapted to be applied, and are pointed at their ends. 85

In practice plumbers and gas-fitters usually prefer a separate wrench for each size of pipe to be handled, and when the wrench is applied to a size of pipe to which it is most efficiently adapted the serrated faces of the 90 jaws engage the pipe practically throughout the combined lengths of the jaws, as best shown in Fig. 1, so as to thereby produce a gripping action which is of maximum efficiency for holding the pipe. This construction, taken in connection with the compounding of the leverage on the jaws through the action of the hand lever 17 and the jaw lever 13 produces a wrench of very 95 high efficiency for holding or turning a pipe or like cylindric object. It will be furthermore noted that the action of the hand lever 17 on the jaw lever 13 is a rolling action throughout the range of movement of the hand lever and that when operating on a 100 pipe of a size to which the wrench is most efficiently adapted this rolling engagement is between the curved wall of the notch 15 and the curved end of the projection 16. When the jaws are further opened or closed 110

to engage over larger or smaller pipes, respectively, the rolling engagement is between the end of the jaw lever at the sides of the notch 15 and shoulders 20 at the sides 5 of the base of the projection 16, as shown in Figs. 3 and 4.

By reason of the fact that the jaws terminate slightly beyond the plane of the axis of the pipe and by reason of the further fact 10 that the jaws are adapted to engage the pipe throughout the combined lengths of the serrated faces thereof, it will be readily seen from an inspection of Fig. 1 that when operating on a pipe that lies against a flat wall, 15 as indicated at 21, ample angular movement of the wrench is permitted to turn the pipe without clashing with the surface of the wall.

While the wrench possesses its highest 20 efficiency when operating upon a diameter of pipe to which the dimensions of the wrench especially adapt it, it will be noted from an inspection of Figs. 3 and 4 that the wrench is also capable of efficient gripping 25 action upon pipes of larger or smaller diameter. Thus when the hand lever 17 is swung to the position shown in Fig. 3 the jaws of the wrench are capable of receiving a pipe or like object of considerably larger 30 diameter than the size to which it is most efficiently adapted. Likewise, when the hand lever 17 is swung to the position shown in Fig. 4 the jaws are capable of grasping a 35 much smaller pipe. It is, of course, true that as the size increases or decreases beyond the theoretical or ideal size for a given wrench the area of contact between the serrated faces of the jaws and the pipe will be somewhat decreased, but in many instances the 40 gripping effect will be entirely efficient. The capacity for grasping larger or smaller

pipes is due to the ability of the shorter hand lever 17 to swing past the plane of the longer hand lever 12 in both directions.

If the jaws 10 and 11 be extended and 45 sharpened, the tool may serve as a hoof clipper, and the arrangement of hand and jaw levers is such as to enable a powerful nipping or cutting action to be exerted on the jaws through the hand levers. 50

I claim as my invention:

A pipe wrench comprising two jaws adapted to embrace a pipe and formed with curved gripping surfaces concentric to the axis of said pipe, said jaws embracing but 55 slightly more than half the circumference of the pipe, a hand lever formed integral with one of said jaws to which the other jaw is pivoted closely adjacent to said gripping surfaces, said latter jaw being provided with 60 a rearwardly extending portion or tail piece provided with a single, rearwardly opening notch having a concave bottom, and a second hand lever pivoted to said first hand lever and provided at its end closely adjacent to 65 said latter pivot with a single projection having a convex end adapted for rolling contact with the concave bottom of said notch, said second hand lever being pivoted to swing across the first hand lever and provided at the sides of its convex end with shoulders to engage shoulders on the tail piece at the sides of said notch, for the purpose set forth. 70

In testimony, that I claim the foregoing as 75 my invention I affix my signature in the presence of two witnesses, this 31st day of December A. D. 1914.

JOHN LA ROCK.
